UNITED STATES PATENT OFFICE.

FREDERICK W. SAUER, OF HOLLIS COURT, NEW YORK, ASSIGNOR TO HOME DEVICES CORPORATION, OF BROOKLYN, NEW YORK, A CORPORATION.

DRIVING MECHANISM FOR LAUNDRY APPARATUS.

1,224,961.

Specification of Letters Patent.

Patented May 8, 1917.

Application filed April 20, 1915. Serial No. 22,545.

To all whom it may concern:

Be it known that I, FREDERICK W. SAUER, a citizen of the United States, residing at Hollis Court, county of Queens, and State 5 of New York, have invented new and useful Improvements in Driving Mechanism for Laundry Apparatus, of which the following is a specification.

The object of the invention is to provide a 10 simple, safe and compact driving mechanism for use, more particularly, with laundry apparatus. The invention comprises certain novel features of construction and combinations of parts, which will be hereinafter described and more particularly pointed out in the claims.

In the drawings:

Figure 1 is a sectional elevation, showing the arrangement of the drive mechanism in 20 relation to a washing machine and a wringer;

Fig. 2 is a sectional side elevation of the motor and therewith incased parts of the driving mechanism;

Fig. 3 is a bottom plan of Fig. 2, with the bottom of the casing cut away;

Fig. 4 is a section on the line 4--4 of Fig. 2;

Fig. 5 is a section on the line 5--5 of Fig. 2;

Fig. 6 is a vertical section on the line 6--6 of Fig. 4;

Fig. 7 is an enlarged fragmentary perspective detail view;

Fig. 8 is a section on the line 8--8 of Fig. 2;

Fig. 9 is a face view of a yielding driving connection seen in Fig. 8;

Fig. 10 is a view similar to Fig. 9, with a 40 part removed;

Fig. 11 is an axial section through Fig. 9;

Fig. 12 is a detail sectional view of a bearing;

Fig. 13 is a side elevation of Fig. 12.

The apparatus to be driven includes a 45 washing machine, which comprises a perforated cylinder, 1 suitably journaled in a tub, 2. The incased driving mechanism, designated generally by the reference character 3, is preferably mounted on top of one wall of the tub, by means of clamp brackets

4, and a wringer 5 driven by the same mechanism is mounted by similar brackets 6 on top of the opposite wall.

The driving mechanism comprises an enclosed electric motor 7, the particular construction of which is not essential to the invention and is therefore, not illustrated in detail. The gearing driven by the motor for operating the washing machine and the wringer is housed within a casing structure, 8, bearing the motor 7 and inclosing spaces beneath and at one side thereof. On the motor armature shaft 9 is a worm 10, which meshes with a worm wheel 11 fast on a transverse shaft 12 below the armature shaft. The said transverse shaft is journaled in bosses 13 on the side walls of the upward extending portion of the casing 8, and has projecting ends 14, each of which is provided with a key 15, so that either or both may receive the ends of flexible driving connections such as indicated at 16 in Fig. 1. In that view the flexible driving connection extends across the top of the tub 2, and connects the shaft 12 with a driving shaft 17 of the wringer 5. The construction of the wringer and its immediate driving mechanism constitutes the subject-matter of a copending application, filed April 20, 1915, Serial Number 22,547, and the flexible driving connection is also covered by a copending application, filed April 20, 1915, Serial Number 22,546. A spur gear pinion 18, of smaller diameter than the worm wheel 11, is mounted on the same shaft 12, and may be connected with and disconnected from the worm wheel in order to throw the washing machine into and out of action. For this purpose the pinion 18 is made loose on the shaft 12, and may be slid thereon by means of a shifter 19 having a bifurcated portion 20 embracing the pinion. The said shifter is itself mounted slidably on a rod 21, and has a downward projecting finger 22 operating in a movement-limiting opening 23 in a horizontal plate 24 forming an internal portion of the casing 8. The lower end of this finger is adapted to be acted upon by a rocker 25 on the end of a horizontal rock-shaft 26. The latter is shown passing lengthwise of the horizontally extending portion of the casing

and provided at its remote end, outside of the casing, with a handle 27. As more clearly shown in Fig. 8, the rocker 25 is provided on its face with pins 28, located at opposite sides of the rocker and spaced apart at a distance greater than the width of the finger 22. With this construction a considerable amount of movement of the rock-shaft 26, amounting to approximately a half turn, is required in order to shift the pinion 18 into or out of coupled relation with the worm wheel 11, thereby insuring against accidental engagement or disengagement of the clutch parts, about to be described, which might occur through a slight blow or jar if only a small movement of the shaft 26 were necessary. In either position of the rock-shaft, it may be noted, the laterally projecting handle 27 is disposed horizontally, so that the weight of this part tends to hold the rock-shaft, and therefore the shifter 19, on the pinion 18 in position. A simple form of clutch has been provided between the pinion and the worm wheel, the same comprising studs 29 and 30 projecting, respectively, from the opposed faces of the worm wheel and of a hub 31 on the pinion, these studs being so arranged that the stud 29 bears laterally against the stud 30 when the pinion is shifted toward the worm wheel, thereby coupling these parts in driving relation.

A slip or yielding connection is provided for permitting the driven portions of the gearing to remain stationary in event of unusual resistance being encountered, thereby avoiding injury which might result, for example, from the washing machine becoming clogged or jammed. The said slip connection includes a disk 32, set into a counter-sunk recess in the face of the worm wheel 11 in such manner as to be capable of turning therein. The said disk is provided with one or more cavities 33 in its outer face, and in these cavities are balls 34, which project slightly beyond the said face so as to enter smaller openings 35 arranged in circular series in a resilient yielding plate 36, which is fixed by screws 37 to the worm wheel. The disk 32 bears the pin 29, and when the resistance to the driving effort of the motor exceeds a safe amount, the annular plate 36 bends sufficiently to slip around over the balls 34. When the resistance decreases, the driving connection is automatically re-established by the plate 36 returning to its original condition with three of its holes 35 engaging the balls 34. The openings 35 are preferably more numerous than the balls 34, the arrangement being such that the balls 60 may enter any three correspondingly spaced openings.

The pinion 18 is in mesh with the large gear 38 fixed to a shaft 39 journaled in the lower portion of the casing. The pinion 12

and gear 38 are preferably of such width ⁸⁵ that they remain in engagement irrespective of the axial shifting movement of the pinion. The gear 38 in turn meshes with a broad idler or intermediate gear 40, fixed on a shaft 80 below the motor, and the gear 40 meshes simultaneously with two pinions 41 and 42, which are disposed in different vertical planes. The pinion 42 forms one of a pair of spaced pinions 42 and 43, which are mounted loosely on a shaft 44, which shaft is to be driven in opposite directions and bears, outside of the casing, a gear 45 in mesh with a gear 47 on the cylinder 1 of the washing machine. The pinion 41 forms one of a pair of pinions 41 and 48, which are ⁸⁰ fixed on a countershaft 49. The pinion 48 meshes with the pinion 43 on the shaft to be driven. From the foregoing it will be understood that the pinion 42 is driven in one direction by the gear 40, while the pinion 43 ⁸⁵ is driven in the reverse direction through the extra intermediate gearing 41, 48. The pinions 42 and 43 may be held against longitudinal movement on the shaft 44 by means of plates 50, which are fixed to a cross-rod ⁹⁰ 51 and enter grooves 52 in the hubs of the said pinions. A double clutch member 53 is mounted slidably on the shaft 44 between the pinions 42 and 43, being coupled to the shaft as to rotation by means of the spline ⁹⁵ 54. This clutch member is provided on its opposite faces with projecting pins 55 adapted to bear against similar pins or studs 56 on the faces of the pinions to drive the latter in the same manner as the clutch heretofore described.

By shifting this clutch member in opposite directions, the pinions 42 and 43 may be coupled alternately with the shaft 44. The shifting is effected automatically through a lever 57, which is fulcrumed intermediate its ends on a vertical axis on top of a post 58, and formed at one end with a fork 59 having studs 60 engaging a circumferential groove in the clutch member 53. At the opposite ¹⁰⁵ end of the lever is a head 61, having spaced longitudinally projecting roller studs 62. A cam 63 operates between these studs, so as to shift the lever first in one direction and then the other, the said cam being fixed to ¹¹⁰ the face of a worm wheel 65 meshed by a worm 66 which is fixed to the shaft 39 of the large gear 38. The shaft 67 carrying the worm wheel 65 and cam 63 is mounted at one end in a hanger 68, depending from the ¹²⁰ shaft 39. The hanger with the worm wheel 65 and cam 63 are held against displacement in one direction by a frame part 69 and in the opposite direction by the lever. The shaft 67 is extended beyond the cam 63, so ¹²⁵ as to enter a horizontally elongated recess ⁷⁰ in the head 61 of the lever, thereby aiding and holding the parts in proper assembly.

This projecting portion of the shaft may be provided with an anti-friction roller 71, indicated in Fig. 5. The cam 63 is preferably so formed as to permit the clutch member 53 to dwell for a suitable period in each of its shifted positions. The connections between the motor and the cam, it will be observed are of a speed-reducing character, so that the reversals are relatively infrequent, as compared with the rate of revolution of the gear 46 driving the washing cylinder.

The post 58 on which the lever 57 is fulcrumed is fixed to a transverse rod 72, which extends across the interior of the casing and is received at its ends in sockets 73 containing springs 74. The said springs, by their opposing action, hold the rod 72 in a mid-position with freedom to yield in either direction if necessary. This is important, since it avoids jamming or breakage in event of one of the pins 55 of the clutch member 53 striking endwise upon a pin 56 of one of the pinions 42, 43, thereby momentarily arresting the movement of the clutch member. In such event, one or other of the springs 74 yields until the pin 55 rides off the pin 56, wheretupon this compressed spring completes the movement of the shift lever and clutch member.

Lubrication of the gears is provided for by receptacles 75 and 76, formed on the bottom of the casing for the reception of oil, through which the teeth of the worm wheel 65 and of the pinions 42 and 43 travel in their revolution.

The ends of the rotary shafts 39, 80 and 49 are journaled in a simple and advantageous form of bearing, illustrated in detail in Fig. 12. As there illustrated, the side wall of the casing is formed with an inwardly projecting boss 81, in which bearing metal 82 is cast. The latter is bored out to receive the end of the shaft, the bore being extended beyond the end of the shaft in the form of a conical- or capped recess 83, the bottom or back of which communicates with the outer face of the bearing plug 82 through a small opening 84. In this way the shaft is held against endwise movement, and lubricant may be introduced through the hole 84 into the cavity 83, the capacity of which is increased by a bore or recess 85 formed in the end of the shaft.

In operation the motor drives the shaft 14 through the worm 10 and worm wheel 11. From either end of this shaft the wringer 5 may be driven, as heretofore explained. The remainder of the train of mechanism within the casing 8 may be started and stopped in order to start and stop the washing machine by turning the handle 27 of the rock-shaft 26, which shifts the pinion 18 into or out of clutch engagement with the worm wheel. The direction of rotation of the driven shaft

44 is reversed automatically by the cam 63 and lever 58 acting upon clutch member 53 in the manner more particularly set forth above. In event of unusual resistance being encountered in the drive of the washing machine, the yielding connection illustrated in Figs. 9 to 11 permits slippage until such time as the resistance decreases or the trouble is rectified.

What is claimed as new is:

1. A reversing gear, comprising a driving shaft, a gear thereon, a broad idler in mesh with and driven by the gear on the driving shaft, two pinions simultaneously in mesh with and driven by said broad idler, a driven shaft whereon one of said pinions is mounted loosely, another pinion loose on the driven shaft, a countershaft whereon the other of the two pinions in mesh with the idler is fixed, and another pinion fixed on this shaft and meshing with the other of the loose pinions on the driven shaft, in combination with a worm on the driving shaft, a worm wheel driven by the worm, a cam united with said worm wheel, a shifter operated by said cam, and a clutch operated by said shifter and located between the loose pinions on the driven shaft to couple the same alternately to the shaft.

2. In a driving and reversing mechanism, a driven shaft, a pair of gears loose on said shaft, a clutch member adapted to couple said gears alternately to their shaft, and a lever for shifting said clutch member, in combination with a shaft, a worm thereon, a hanger on this shaft, a worm wheel having a shaft mounted on said hanger, and a cam united with said worm wheel for operating the shifting lever, said lever having a slotted recess in its end into which the end of the worm wheel shaft projects.

3. The combination with a gearing, of a lever controlling the same, a shaft, a worm thereon, a hanger on said shaft, a worm wheel having a shaft mounted on said hanger, and a cam united with said worm wheel for operating the shifting lever, said lever having a slotted recess in its end into which the end of the worm wheel shaft projects.

4. The combination with a gearing, of a lever controlling the same, said lever having a pair of spaced studs at one end and a slotted recess between said studs, a shaft bearing a cam between said pins, the said shaft entering the recess in the lever, and means for driving the cam.

5. In a driving and reversing mechanism, the combination with a driven shaft, a pair of gears loose on said shaft, a clutch member adapted to couple said gears alternately to their shaft, and a lever for shifting said clutch member, of power-driven means for operating said lever, and resilient means

yieldingly holding the fulcrum of said lever in a mid-position and permitting displacement thereof to one side or the other.

6. The combination of a clutch, a lever for operating the same, a cam for operating the said lever, a support on which said lever is fulcrumed, and spring means yieldingly holding said support in a mid-position and

permitting displacement thereof laterally of the fulcrum.

Dated, April 15th, 1915.

FREDERICK W. SAWER.
